(57) **CLAIM**

The ornamental design for a magnetic resonance treatment system, as shown and described.

DESCRIPTION

FIG. 1 is a rear, right side perspective view of a magnetic resonance treatment system with a headset positioned on a mount, wherein the back, left perspective view is a mirror image of the back, right side perspective view with the exception of the adjustable strap and connection cord on the headset that are unclaimed parts of the system;

FIG. 2 is a front view of the magnetic resonance treatment system illustrated in FIG. 1;

FIG. 3 is a rear view of the magnetic resonance treatment system illustrated in FIG. 1;

FIG. 4 is a right side view of the magnetic resonance treatment system illustrated in FIG. 1;

FIG. 5 is a left side view of the magnetic resonance treatment system illustrated in FIG. 1;

FIG. 6 is a top elevation view of the magnetic resonance treatment system illustrated in FIG. 1;

FIG. 7 is a bottom elevation view of the magnetic resonance treatment system illustrated in FIG. 1; and,

FIG. 8 is a rear, right side perspective view of the magnetic resonance treatment system with the headset and mount shown as two separable components.

The even-length broken lines in the drawings illustrate portions of the magnetic resonance treatment system that form no part of the claimed design. The dot-dash broken lines in FIG. 8 are for the sake of showing the assembly and form no part of the claimed design.

1 Claim, 8 Drawing Sheets
